UNITED STATES PATENT OFFICE.

BYRD W. BALLOU, OF BUFFVILLE, KANSAS.

METHOD OF ORNAMENTING BRICK.

1,179,601.

Specification of Letters Patent. Patented Apr. 18, 1916.

Application filed May 26, 1915. Serial No. 30,653.

To all whom it may concern:

Be it known that I, BYRD W. BALLOU, a citizen of the United States, residing at Buffville, in the county of Wilson and State 5 of Kansas, have invented new and useful Improvements in Methods of Ornamenting Brick, of which the following is a specification.

This invention relates to an improved 10 method or process for producing ornamental designs upon the exposed faces of brick, and particularly relates to the treatment of the clay-brick ribbon as it passes from the form or mold.

15 Prior attempts have been made to ornament brick by the treatment of the brick ribbon when green or wet, but when the articles thus produced are built into a wall, the wall has the appearance of being water-streaked. This disfigurement of the wall is 20 incidental to the severe vertical transverse lines of the designs produced, and the various methods employed.

It is an object of this invention to produce 25 a method which treats the green brick ribbon by one operation to produce upon the subsequently exposed faces of the brick cut therefrom an ornamental design imparting a "rough" appearance to the brick and to 30 the completed wall without the severe vertical or horizontal lines of prior ornamented brick, and to provide a method for ornamenting brick in which the design may be varied.

35 The method forming the present invention is carried out by the machine of the novel construction hereinafter set forth, and which is made subject matter of a companion application filed of even date herewith, 40 the same being disclosed in the accompanying drawings wherein—

Figure 1 is a side elevation of the brick ornamenting machine of this invention. Fig. 2 is a top plan view of the same. Fig. 3 is 45 a transverse section on the line 3—3 of Fig. 1, taken through the brick ribbon forwardly of the ornamenting device and looking toward the same. Fig. 4 is a detail enlarged bottom plan view of the upper surface of the ornamenting or marking mechanism. Fig. 5 is a detail perspective view of the finished article produced by the method of this invention. Fig. 6 is a transverse section taken on the line 6—6 of Fig. 1, through the 55 side or edge marking mechanism. Fig. 7

is a detail enlarged fragmentary view of the marking pins and guide therefor applied to the upper surface of the brick ribbon.

Referring to the accompanying drawings, 10 designates a brick ribbon support, shown 60 in the present instance in the form of a conveyer or endless belt which, as usual, is adapted to support and carry the brick ribbon 11 from the die or former, not shown. The endless belt or conveyer 10 is disclosed 65 as supported at one end upon a pulley 12 mounted on a shaft 13, the latter provided upon its end with a sprocket wheel 14 for a purpose which will hereinafter appear. A substantially U-shaped frame 15, open at its 70 lower end, is supported above the brick ribbon 11 upon suitable braces 16. In the opposite ends of the frame 15 are supporting wheels 17 carried upon vertical shafts 18 and 19. The wheels 17 support an endless 75 carrier 20 adapted to move in an endless path above the brick ribbon 11. The frame 15 carries upon its upper side a horizontal shaft 21 connected to the shaft 18 by bevel gears 22 and having upon its end a sprocket 80 wheel 23 which is connected to the sprocket wheel 14 of the conveyer mechanism by means of a chain 24. The object of this arrangement is to drive the endless carrier 20 simultaneous with and at the desired proportionate speed relative to the endless conveyer 10.

Mounted upon the carrier 20 is a plurality of vertically-movable downwardly projecting pins 25. The pins 25 are normally held 90 up out of contact with the upper face of the brick ribbon 11 by means of springs 26, each spring 26 surrounding its pin 25 and being held between the head of the pin and the upper edge of the carrier 20.

The frame 15 is provided in its upper end with a pin adjusting plate 27 supported upon set screws 28 passing through the frame 15. The plate 27 receives the inner ends of the pins 25 and has upon its lower face near its forward and rear edges guides or cams 29 which lie in the path of the heads of the pins 25 to depress the pins and hold the same down during their passage across the upper face of the brick ribbon 11. It will be noted from Figs. 3 and 7 that the cams or guides 29 are so placed that the pins 25 in moving toward the edge of the brick ribbon are depressed prior to their engagement with the brick ribbon. The 105 110

pins are held down in engagement with the brick ribbon until they reach a point near the opposite edge of the brick ribbon when they are abruptly released out of contact with the ribbon to prevent the breaking away or crumbling of the edge of the ribbon by the pins as they are drawn laterally out of contact therewith.

The frame 15 is provided preferably upon one end with a yoke 30 in which are journaled the opposite ends of the shaft 19. A set screw 31 is carried by the yoke 30, and engages the end of the frame 15 to adjust the yoke longitudinally upon the end of the frame 15 and draw the shaft 19 through the slots 32 in the frame to adjust the tension of the endless carrier 20.

It is desired not only to ornament that portion of the brick ribbon which subsequently becomes the outer faces of the brick, but also the sides or edges of the brick ribbon which later become the opposite ends of the brick and which are disclosed to view in the construction of walls and the like. To ornament the edges of the brick ribbon a substantially hollow rectangular frame 33 is arranged in advance of the upper surface ornamenting mechanism above described, and surrounds the brick ribbon 11, as shown to advantage in Fig. 6. In this frame 33 there are arranged a pair of vertically disposed and spaced-apart endless carriers 34, each having inwardly extending pins 35 adapted to engage the opposite edges of the brick ribbon 11 and being normally urged away from the brick ribbon by springs 36. The springs 36 surround the inner ends of the pins and are held between the outer faces of the endless conveyors 34 and the heads of the pins. Adjusting plates 37 are also arranged within the frame 33 to receive thereaegard the heads of the pins 35. Set screws 38 support the plates 37 and serve to advance or retard the same toward the opposite sides or edges of the brick ribbon to vary the depth of marking by the pins 35. The pins 35 are brought into engagement with the opposite sides of the brick ribbon 11 by the cams 39 which are of substantially the same formation and operate in the same manner as do the cams 27 hereinabove referred to. The lower ends of the endless carriers 34 are mounted upon sprocket wheels 40 fixed to a transverse shaft 41 passing beneath the brick ribbon 11 and journaled in the sides of the frame 33. The upper ends of the carriers 34 are mounted on sprockets 42 fixed upon a transverse shaft 43 passing over the top of the brick ribbon 11 and being journaled at its opposite ends in a yoke 44. The yoke 44 is supported upon set screws 45 engaging the frame 33 to raise or lower the yoke and thus vary the tension of the endless carriers

34. The lateral marking mechanism thus described is driven or actuated by a chain 46 which passes over a sprocket 47 fixed preferably upon an intermediate portion of the shaft 43, and which also passes over a sprocket 48 fixed to the transverse shaft 21 of the upper surface marking mechanism. With this arrangement it is thus seen that the top and lateral marking mechanisms are simultaneously operated, and that this operation is proportionate to the operation of the carrier or table upon which the brick ribbon is supported.

As the pins 25 and 35 are mounted on endless carriers 20 and 34 respectively, the pins 25 are moved across the surface of the brick ribbon first in one direction and then in an opposite direction. As the brick ribbon 11 is moved continuously forward during this back and forth travel of the pins, the pins first striking the brick ribbon cut into the surface diagonal lines extending in one direction and subsequently these lines are intersected by the oppositely extending diagonal lines of the pins when they are drawn across the brick ribbon in the opposite direction. These pins not only mark lines in the surface of the brick ribbon but also roughen or disturb the surface so as to impart a rugged appearance to the ornamented surface, and produce a somewhat indistinct design of diamond-shape, dependent upon the proportionate speeds of the brick ribbon and the marking pins.

It is, of course, understood that various other machines or modifications of the above described mechanism may be employed for carrying out the method of this invention as will be understood within the scope of the following claims.

What I claim is:—

1. The method of ornamenting brick which consists in moving a brick ribbon, and simultaneously operating a marking device across the face of the brick ribbon in a direction at right angles to the direction of travel of the same.

2. The method of ornamenting brick which consists in moving a brick ribbon longitudinally, and passing cutters transversely across the face of the brick ribbon simultaneously with the longitudinal movement thereof.

3. The method of ornamenting brick which consists in advancing a brick ribbon and passing spaced-apart cutters transversely across the face of the brick ribbon simultaneously with the advancing thereof, whereby to form a plurality of parallel oblique lines in the face of the brick ribbon.

4. The method of ornamenting brick which consists in moving a brick ribbon longitudinally, and operating spaced-apart cutters transversely across the face of the brick ribbon simultaneously with the longi-

tudinal movement thereof, whereby to form oblique parallel lines in the face to be ornamented.

5. The method of ornamenting brick which consists in simultaneously advancing a brick ribbon, and operating a marking device across the face of the brick ribbon transversely to the direction of travel of the brick ribbon and simultaneously with the 10 movement thereof.

6. The method of ornamenting brick which consists in advancing a brick ribbon, and simultaneously moving a cutter across the face of the moving brick ribbon at a 15 speed relative thereto, whereby to cut oblique lines at the desired angle in the face to be ornamented.

7. The method of ornamenting brick which consists in advancing a brick ribbon, 20 and operating a marking device across the face of the brick ribbon transversely to the direction of movement of the brick ribbon and at a relative speed thereto, whereby to form oblique designs at the desired angle 25 in the face to be ornamented.

8. The method of ornamenting brick which consists in advancing a brick ribbon, and operating a marking device across the face of the brick ribbon in opposite directions 30 transversely to the direction of movement of the brick ribbon, whereby to form oblique crossed lines in the face to be ornamented.

9. The method of ornamenting brick

which consists in advancing a brick ribbon, 35 and operating a marking device across the face of the brick ribbon in opposite directions transversely to the direction of movement of the brick ribbon and at the desired relative speed thereto, whereby to form 40 designs of the desired shape in the face to be ornamented.

10. The method of ornamenting brick which consists in advancing a brick ribbon and operating marking devices against the 45 upper face and edges of the brick ribbon to form designs therein and at a speed proportionate to the advancement of the brick ribbon, whereby to vary the shape of the 50 designs.

11. The method of ornamenting brick which consists in advancing a brick ribbon and operating marking devices across the top and edges of the brick ribbon in opposite directions transversely to the direction 55 of movement of the brick ribbon and at the desired speed relative thereto whereby to form crossed designs of the desired configuration in the top and edges of the brick ribbon.

In testimony whereof I have hereunto set my hand in presence of two subscribing witnesses.

BYRD W. BALLOU.
